ATTACHMENT FOR FIREARMS

Alonzo F. Gaidos, Redwood City, Calif.

Application January 15, 1935, Serial No. 1,938

16 Claims. (Cl. 42-77)

This invention relates to auxiliary attachments for firearms.

An object of the invention is to provide means for a firearm whereby different ammunition from that normally used in the firearm can be handled and utilized in the firearm.

Another object of the invention is to provide auxiliary attachments for firearms and particularly for revolvers of the single or double action types for quickly and conveniently transforming firearm designed to shoot center fire ammunition, to an arm utilizing inexpensive rim-fire ammunition, such as the standard commercial .22 caliber cartridges.

Another object of the present invention is to generally improve and simplify the construction and operation of repeating auxiliary attachments for revolving firearms by fitting such arms conveniently with sub-caliber barrels and means to utilize rim-fire ammunition which may be fired by the center-fire mechanism of the firearm.

Any firearm so fitted may be employed for economical target practice or for hunting of small game which large caliber cartridges would blow to pieces.

Another object and advantage will be apparent during the course of the following description.

The invention is shown by way of illustrations in the accompanying drawings in which:

Figure 1 is a side view of a revolving type of firearm of the swing-out cylinder magazine type.

Figure 2 is a partial longitudinal cross section of the mechanism.

Figure 3 is a rear view of the firing-pin block.

Figure 4 is a section through 4-4 of Fig. 2.

Figure 5 is a side view of the cylinder magazine units in the act of ejecting fired cartridge cases.

Figure 6 is a rear view of a swing-out cylinder type of firearm fitted with my device.

Figure 7 is a side view of a break-open type of revolving firearm fitted with my device.

Figure 8 is a side view of a solid frame, ejector-rod type of firearm fitted with an alternate arrangement of my caliber device.

Figure 9 is a rear view of firing-pin block for use on a firearm of the type shown in Figure 8.

Referring more particularly to Figure 1, I provide a sub-caliber tube 1, having an enlarged knurled portion 2, on one end and a threaded portion 3, on the other end. The sub-caliber tube 1, is inserted from the muzzle end of the arm until it comes to rest on shoulder 2', of the sub-caliber tube 1. A lock nut 4, engages threaded portion 3, on opposite end and securely retains the tube 1, in the barrel of the arm.

I then provide a cylinder 5, having bored holes 6, equally spaced around a circle to receive rim-fire cartridges 7, so that they are in proper alignment with the sub-caliber tube 1. I also provide an ejector plate 8, secured to the enlarged end 13, of an ejector rod 13' by means of a pin 10.

The ejector rod 13' is slidably mounted in the swinging crane 14, the upper portion of which terminates in a tubular section 11. Around the enlarged portion 13, of the ejector-rod 13' is freely mounted a coiled spring 12, of the compression type, one end of which rests against a shoulder 15 of the ejector-rod 13', the other end resting against a threaded closure ring 16, screwed into the tubular section 11, of the crane 14.

I also provide an aligning pin 19 on the ejector plate 8 to insure proper alignment of the plate 8 with the cartridge chambers 6, when it is returned to position after ejecting the cartridges. The ejector plate 8 is placed in a recess or counter sunk bore in the adjacent face of the cylinder 5.

I also provide a firing-pin block 17, into which is counter-bored a hole 18, to receive the hub 8' of the ejector plate 8. In the firing-pin block 17, are provided holes 19', to receive plunger firing-pins 20, which are slidably retained by a crimp 21, around each hole 19'. A compression spring 22, is provided to return the plunger firing-pin 20, to the proper position. It will be noted that each plunger 20 is so formed that when struck by the hammer 23, of the firearm at a projecting point 24, the blow will be transferred through an off-center projection 27' at the other end of the plunger 20 to the rim 7' of the cartridge 7, thus exploding the charge. The firing pin block 17, is provided with a usual ratchet 26, which is actuated by the hand in the revolving mechanism of the firearm.

To properly align the firing-pin block 17, so that each plunger 20 is directly over a cartridge 7, I provide a locating pin 27 fixed in the block 17, to freely engage a register hole 28, in the cylinder magazine 6.

The firing pin block 17, has the conventional register stops 30, spaced around its periphery to align the cylinder openings 6, with tube 1. I also provide the block 17 with a relief portion 29, to clear the stop-lug 29' on the frame of 50 the firearm. Thus it will be noted that when the cylinder is in the swung-open position as shown in Figure 6, and rotated so that notch 29, is opposite stop-lug 29', the block 17, may be conveniently detached from the cylinder 5, for the 55

purpose of loading with cartridges or ejecting fired cartridges as the case may be.

I wish it understood that the entire assembly as described is a self-contained unit and may be 5 readily substituted by a cylinder and crane unit of the firearm for which it is designed.

I also wish it understood that my invention may be incorporated for revolving firearms of all types such as those shown in Figure 7, and Figure 8. 10 In the break open type shown in Figure 7, my device is the same as in the swinging crane type, heretofore described. In Figures 8 and 9, which illustrate a solid frame ejector-rod type of firearm, I provide a similar arrangement to that 15 shown, with the exception of omitting the ejector plate 8; and providing a firing pin block 31, having openings 32, between plungers 33, so that the cartridges may be ejected from the cylinders 34, through openings 32, of block 31. There is one 20 such opening 32 between each pair of adjacent plungers 33. Said plungers 33 are arranged similar to plungers 30. A locking mechanism 35, is provided to retain the block 31, in a fixed position while ejecting or loading cartridges. This locking 25 mechanism 35 in the herein illustration includes a latch 36 slidable on the side of the block 31, and a pair of keeper notches 37 and 38 on the cylinder 5 to be engaged by the latch 36, respectively when the plungers 20 or the openings 32 are held in 30 alignment with the cartridges 7.

While certain features of my invention are more or less specifically described, I wish it understood that various changes may be resorted to within the scope of the appended claims. Similarly, that the materials and finish of the several 35 parts employed may be such as the manufacturer may decide on, or varying conditions or uses may demand.

Having thus described my invention, what I 40 claim and desire to secure by Letters Patent is:

1. An auxiliary cylinder for firearms with revolving cylinders, comprising a cylinder with holes to hold sub-caliber ammunition, a separate and detachable firing-pin block on the firing end of 45 the cylinder, and a plurality of firing-pins in the block operatively aligned with the respective ammunition in the holes of the cylinder and being adapted to transmit an impact from a firing mechanism of said firearm to the respective ammunition.

50 2. An auxiliary cylinder for firearms with revolving cylinders, comprising a cylinder with holes to hold sub-caliber ammunition, a separate firing-pin block on the firing end of the cylinder, and a plurality of firing-pins in the block operatively aligned with the respective ammunition in the holes of the cylinder and being adapted to transmit an impact from a firing mechanism of said firearm to the respective ammunition, said firing pin block being detachably held on said cylinder.

55 3. An auxiliary cylinder for firearms with revolving cylinders, comprising a cylinder with holes to hold sub-caliber ammunition, a separate firing-pin block on the firing end of the cylinder, a plurality of firing-pins in the block operatively aligned with the respective ammunition in the holes of the cylinder and being adapted to transmit an impact from a firing mechanism of said firearm to the respective ammunition, and means 60 for aligning the firing-pin block with the holes of said cylinder.

65 4. An auxiliary cylinder for firearms with revolving cylinders, comprising a cylinder with holes to hold sub-caliber ammunition, a firing-pin block 70 on the firing end of the cylinder, a plurality of

firing-pins in the block operatively aligned with the respective ammunition in the holes of the cylinder so as to transmit an impact from a firing mechanism of said firearm to the respective ammunition, an ejector plate disposed between the 5 end of the cylinder and the firing-pin block, and means whereby the ejector plate can be manipulated to move said firing pin block away from the end of the cylinder and to eject said ammunition from said holes.

10 5. An auxiliary cylinder for firearms with revolving cylinders, comprising a cylinder with holes to hold sub-caliber ammunition, a firing-pin block on the firing end of the cylinder, a plurality of firing-pins in the block operatively aligned with 15 the respective ammunition in the holes of the cylinder so as to transmit an impact from a firing mechanism of said firearm to the respective ammunition, an ejector plate disposed between the end of the cylinder and the firing-pin block, and 20 means whereby the ejector plate can be manipulated for simultaneously moving said block away from said cylinder and ejecting said ammunition from said cylinder, said ejector plate being centrally located relatively to and being recessed into 25 said end of the cylinder.

6. The combination with a cylinder for a firearm having holes to contain ammunition, of a firing-pin block at the end of the cylinder adjacent the firing mechanism of the firearm, a plurality of rim-fire firing pins in said block being aligned with the holes of the cylinder, said pins being adapted to be actuated by a center fire firing mechanism of the firearm, and means for moving said firing block relatively to said cylinder and to 30 simultaneously eject the ammunition or shell from 35 said cylinder.

7. The combination with a cylinder for a firearm having chambers to contain ammunition and an ejector element adapted to be extended through 40 the respective chambers to eject the ammunition therefrom, of a firing block on an end of the cylinder, firing pins in said block to transmit the action of the firing mechanism of the firearm to said ammunition, said block being apertured in 45 offset relation to said pins to allow the ejection of the ammunition through the firing block when the block is shifted to align its aperture with the respective chambers of the cylinder.

8. The combination with a cylinder for a firearm having chambers to contain ammunition and an ejector element adapted to be extended through the respective chambers to eject the ammunition therefrom, of a firing block on an end of the cylinder, firing pins in said block to 55 transmit the action of the firing mechanism of the firearm to said ammunition, said firing block having a set of holes therethrough corresponding to the chambers in the cylinder and being offset relatively to the firing-pins, said firing block being 60 adapted to be adjusted for selective alignment of either said firing-pins or said holes with the respective chambers of the cylinder, said holes being adapted to allow ejection of ammunition there-through.

65 9. The combination with a cylinder for a firearm having chambers to contain ammunition and an ejector element adapted to be extended through the respective chambers to eject the ammunition therefrom, of a firing block on an end 70 of the cylinder, firing pins in said block to transmit the action of the firing mechanism of the firearm to said ammunition, a set of holes in said firing block corresponding to the chambers in the cylinder and being offset relatively to the firing- 75

- pins to allow the ejection of ammunition when the firing block is adjusted so as to bring the holes of the firing block into alignment with the chambers of the cylinder, and means to selectively hold the 5 firing block relatively to said cylinder either with the firing pins or with holes of the block in registry with the chambers of the cylinder.
10. The combination with a magazine for a firearm adapted to hold ammunition in operative 10 relation to the barrel of the firearm, and a firing mechanism of said firearm, of a removable firing-pin block at the end of the magazine adjacent said firing mechanism, a plurality of firing pins in said block being aligned with said ammunition in the 15 magazine, said pins being adapted to transmit the usual impact of said firing mechanism to said ammunition.
11. The combination with the usual barrel of a 20 revolver having means behind the barrel to support a usual cylinder between a firing mechanism and the barrel, and a sub-caliber barrel adapted to be arranged in said usual barrel, of a cylinder having permanent sub-caliber chambers therein taking the place of said usual cylinder and fitting 25 between the sub-caliber barrel and said firing mechanism, a block detachably arranged on the end of said sub-caliber cylinder adjacent said firing mechanism, a plurality of auxiliary firing mechanisms supported as a unit in said block, and 30 means to align said block so that each auxiliary firing mechanism is in registry with a chamber of said sub-caliber cylinder.
12. The combination with the usual barrel of a 35 revolver having means behind the barrel to support a usual cylinder between a firing mechanism and the barrel, and a sub-caliber barrel adapted to be arranged in said usual barrel, of a cylinder having permanent sub-caliber chambers therein taking the place of said usual cylinder and fitting 40 between the sub-caliber barrel and said firing mechanism, a plurality of auxiliary firing mechanisms supported on said block in registry with the respective chambers of said sub-caliber cylinder, each of said auxiliary firing mechanisms being 45 adapted to convert the action of the usual firing mechanism of said revolver to rim firing action on the sub-caliber ammunition in the chambers of said sub-caliber cylinder.
13. The combination with a revolver of the 50 character described, and a sub-caliber barrel adapted to be arranged in the usual barrel of said revolver, of an auxiliary cylinder for replacing the usual cylinder of said revolver and having sub-caliber chambers therein, a plurality of auxiliary 55 firing mechanisms, a separate element movable relatively to said auxiliary cylinder to support all of said auxiliary firing mechanisms as a unit in alignment with the respective chambers of said
- auxiliary cylinder, and ejector means to move said element and said auxiliary firing mechanisms as a unit when the shells of the ammunition are ejected from said chambers.
14. The combination with the usual barrel of a 5 revolver having means behind the barrel to support a usual cylinder between a firing mechanism and the barrel, and a sub-caliber barrel, of a cylinder having sub-caliber chambers therein taking the place of said usual cylinder, said sub-caliber 10 chambers being shorter than the usual cylinder so as to fit sub-caliber ammunition in length, means to extend the throat of the sub-caliber barrel to one end of said chambers in firing position, and means between the other end of said sub-caliber 15 cylinder and the firing mechanism to transmit the firing action of the latter to the individual chambers.
15. In a device of the character described the combination with the barrel, the frame and the 20 firing mechanism of a revolver, of a sub-caliber barrel detachably arranged in said barrel, a cylinder having sub-caliber chambers therein being arranged in place of the usual cylinder on said frame, said sub-caliber chambers being shorter 25 than the chambers of the usual cylinder of said revolver so as to conform to the length of sub-caliber ammunition, means to extend the throat of the sub-caliber barrel to an end of said chambers in firing position, and means between the 30 cylinder and the firing mechanism to extend the action of said firing mechanism individually to the other end of said sub-caliber chambers.
16. In a device of the character described, the combination with the usual barrel, the frame and 35 the usual firing mechanism of a revolver, the distance between the throat of said usual barrel and said firing mechanism normally accommodating a usual caliber cylinder; of a sub-caliber barrel detachably arranged in said usual barrel, a sub- 40 caliber cylinder arranged in place of the usual cylinder on said frame between said sub-caliber barrel and said firing mechanism, said sub-caliber cylinder having sub-caliber chambers therein, each sub-caliber chamber being substantially of 45 the same length as the sub-caliber ammunition used therein but shorter than said normal cylinder, means at the throat of the sub-caliber barrel to extend the same to the end of the sub-caliber chambers in firing position in axial alignment 50 with said chambers, and auxiliary firing mechanism between the other end of the sub-caliber cylinder and said firing mechanism to transmit and extend the action of the normal firing mechanism through the space between said chambers 55 and the normal firing mechanism to the sub-caliber ammunition in said chambers.

ALONZO F. GAIDOS.
